UNITED STATES PATENT OFFICE.

JAMES PHILIP ERIE, OF NEW YORK, N. Y., ASSIGNOR TO THE ERIE EXPLO-
RATION COMPANY, OF SAME PLACE AND DOVER, DELAWARE.

RHEOSTATIC SUPPORT.

SPECIFICATION forming part of Letters Patent No. 673,392, dated May 7, 1901.

Application filed September 13, 1900. Serial No. 29,928. (No model.)

To all whom it may concern:

Be it known that I, JAMES PHILIP ERIE, a citizen of the United States, residing in the city, county, and State of New York, have invented certain new and useful Improvements 5 in Rheostatic Supports, of which the following is a specification.

My invention relates to rheostatic supports, and has for its object to provide a cheap, simple, and effective support adapted to be used 10 in connection with rheostats and the like; and the invention consists in an insulator strip or core, constituting the support for the electric conductor, embodying the features 15 of construction and arrangement and adapted to be assembled in the manner hereinafter more fully set forth.

Referring to the accompanying drawings, Figure 1 is a perspective view of the preferred 20 form or embodiment of my invention. Fig. 2 is a side view. Fig. 3 is an edge view; Fig. 4, an end view; Fig. 5, a horizontal section. Figs. 6 to 9 are views showing ways of combining or assembling the cores or strips.

In the construction of electric rheostats and 25 similar devices it is desirable to provide a suitable insulator strip or core upon which the conductor may be mounted and secured, and it is one of the principal objects of my 30 present invention to provide such a strip or core and one in which the conductor can be securely held, so that the parts of the conductor will not touch each other, but will be held at proper intervals from each other, and 35 so that the conductor will not be liable to contact with extraneous devices in connection with which the core may be used; and it is further an important object of my invention to provide what may be called a "standard" 40 strip or core so constructed and arranged that it is adapted to be assembled in various relations in making up the desired quantity of resistance or a desired-sized rheostat, and for this purpose I have made a core, which 45 may be termed a "unit-core," having the characteristics above set forth and adapted to be assembled in many practical relations, so that any desired number of units may be used in the most compact manner and without 50 danger of interference with the conductor

by their arrangements with relation to one another or with surrounding objects. With this general statement I will now describe the construction illustrated in the drawings, and I will state that the strip or core may be made 55 of any suitable material, but preferably of porcelain molded in the form shown.

The strip or core comprises a body portion 1, which is preferably rectangular in shape, and it may be of any desired length, width, 60 or thickness, and its edges 2 3 are preferably square, although they may be rounded, as indicated at 3 in Fig. 5.

Arranged longitudinally of the strip on one or both sides, and preferably both, are one 65 or more rows of projections 4, one being shown in the drawings, as this is the preferred form, and these projections are properly spaced to form recesses 5 to receive the conductor, and these recesses of course will be of a width and 70 the projections also, according to the size of the conductor or wire intended to be used and the number of turns of the conductor to be applied to the core. These projections may be of any shape; but preferably they are angular projections, as indicated at 4 in Fig. 3. One end of the body portion is provided with what I term a "footpiece" 6, having side extensions 7 7^a and edge extensions 8 8^a, and one of these edge extensions, as 8, is provided 80 with a tongue, as 9, and the other, as 8^a, is provided with a groove, as 9^a. The side extensions are also provided with grooves, as 10 10^a, which in the present instance are shown as V-shaped and as arranged adjacent 85 to the projections 4, and preferably I arrange two grooves in each extension, as 10 and 10^b and 10^a and 10^c. The object of the tongue and grooves on the footpiece is to aid in assembling the units or strips, as hereinafter 90 set forth, and the object of the grooves 10 to 10^c is to furnish a passage for the wire or conductor, so that it shall be within the compass of the strip. The footpiece is also provided with a recess 11, (best shown in Fig. 4,) and, 95 further, it is provided with a number of transverse openings 12. The object of the recess is to receive an extension on the upper end of another unit, as hereinafter described, and the purpose of the openings 12 is to either re- 100

ceive the wire or conductor when necessary or to receive a bolt or other device for securing a number of units or strips together when they are properly assembled. The body portion is also provided with a headpiece 13, which has side extensions 14 14^a and edge extensions 15 15^a, one of the edge extensions being provided with a tongue 16 and the other with a groove 16^a, and the side extensions are provided with grooves 17^c and 17^a, similar to the grooves 10^c 10^a. The headpiece 13 is also provided with an extension 18 of a shape to fit the recess 11 in the footpiece, and the edge or face of this extension is preferably corrugated, as at 18^b, to expose the openings 12 when two of the units are placed together end to end and as clearly shown in Fig. 7.

In actual practice when the units or strips 20 are molded of course each unit or strip is made integral in all its parts, and that is the preferred form, although, of course, the parts could be made separately and secured together in any well-known way.

25 Such being the construction of the strip or core as a unit, it is evident that the units can be used separately or that they can be combined and assembled in various ways and relations, so that a rheostat or similar device of any desired size can readily be made, and I have illustrated various ways of arranging them sufficient to enable those skilled in the art to use the same. Thus in Fig. 6 I have shown a bottom view of three units arranged in the 30 same plane or edge to edge, and it will be seen that the tongues 9 engage the grooves 9^a of the adjacent strips.

In Fig. 7 I have shown a partial view of two units arranged end to end, and it will be 40 seen that the extension 18 fits into the recess 11 of the adjacent strip, and the grooves 10 10^a are so related that the ends of the conductors on the units may be united.

In Fig. 8 I have shown an end view of two 45 units placed side to side, and in Fig. 9 I have shown four units placed in rows of two.

It will be evident that these arrangements 50 may be multiplied and any desired number of units assembled in proper relation to each other and that they will occupy the least possible space and that the side and edge extensions of the head and foot pieces of one unit will rest upon the similar extensions of the other or others and under all conditions 55 the conductor will be properly insulated. Furthermore, if any one or more of these units are inclosed in a case the side and edge extensions as well as the projections on the sides of the body will serve to support the 60 case and keep it from coming in contact with the conductor.

The description so far given is sufficient 65 to enable those skilled in the art to make and use my invention in the best manner to suit any particular circumstances or conditions, and it will be seen that each unit is complete in itself and that it may be cheaply

made and that the conductor is effectively insulated under all conditions.

The core or strip is provided with extensions and projections, which protect the conductor and form interlocking portions where a number of units are assembled. It is evident that the shape of the extensions and projections may be varied to suit different 75 conditions without avoiding the spirit of my invention. It will also be understood that while I have shown the core or strip as used in connection with a rheostat it may of course be used in connection with other devices to which the same is adapted without departing from the invention.

What I claim is—

1. An insulating core or support for electric conductors comprising a body portion provided with interlocking portions whereby a core is adapted to interlock with a similar core, substantially as described. 85
2. An insulating core or support for electric conductors comprising a body portion provided with a foot and head piece having side and edge extensions, substantially as described. 90
3. An insulating core or support for electric conductors comprising a body portion provided with a foot and head piece having side and edge extensions provided with a tongue and groove, substantially as described. 95
4. An insulating core or support for electric conductors comprising a body portion provided with a foot and head piece having side extensions provided with grooves, substantially as set forth. 100
5. An insulating core or support for electric conductors comprising a body portion provided with a foot and head piece having side extensions provided with grooves, and edge extensions provided with a tongue and groove, substantially as described. 105
6. An insulating core or support for electric conductors comprising a body portion provided with a foot and head piece, one having a recess in its end and the other an extension adapted to fit such a recess, substantially as described. 110
7. An insulating core or support for electric conductors comprising a body portion provided with a foot and head piece, one having a recess and openings in its end and the other having an extension with a corrugated face, 115 substantially as described. 120
8. An insulating core or support for electric conductors comprising a body portion provided with a foot and head piece and having projections on its sides, substantially as described. 125
9. An insulating core or support for electric conductors comprising a body portion provided with a foot and head piece having side and edge extensions provided with interlocking portions, and having projections on its sides between the head and foot pieces, substantially as described. 130
10. An electric rheostat, comprising a plu-

5 rality of insulating-strips each strip comprising a body portion and having head and foot extensions and provided with interlocking portions, whereby the interlocking portions of the separate strips may engage each other to form a rheostat embodying a plurality of insulating-strips, substantially as described.

In testimony whereof I have signed my name to this specification in the presence of two subscribing witnesses.

JAMES PHILIP ERIE.
